(57) **CLAIM**

The ornamental design for a gun rack, as shown and described.

DESCRIPTION

FIG. 1 is a perspective front view of the gun rack, showing my new design;

FIG. 2 is a front side view thereof;

FIG. 3 is a back side view thereof;

FIG. 4 is a left side view with the right side view being a mirror image thereof;

FIG. 5 is a top side view thereof; and,

FIG. 6 is a bottom side view thereof.

The broken line showing in the figures is included for the purpose of illustrating portions of the gun rack and form no part of the claimed design.
